UNITED STATES PATENT OFFICE.

JOSEPH L. HERZOG, OF NEW ROCHELLE, NEW YORK.

DESIGN FOR A FINGER RING OR SIMILAR ARTICLE.

Application filed August 6, 1925. Serial No. 14,330. Term of patent 14 years.

To all whom it may concern:

Be it known that I, JOSEPH L. HERZOG, a citizen of the United States, and resident of New Rochelle, county of Westchester, State of New York, have invented a new, original, and ornamental Design for a Finger Ring or Similar Article, of which the following is a specification.

In the accompanying drawings forming part of this specification the design is illustratively shown as applied to the whole of the surface of a ring of the wedding ring type; and Fig. 1 is a side view of such a ring embodying the design, and Fig. 2 is an edge view thereof.

As shown in Fig. 1, the side portions of the foundation metal of the ring are developed as a series of scallops or serrations *a* with intermediate recesses *b*. The edge of the ring as indicated at *c* in Fig. 2 is engraved to produce a noticeable glittering effect. The scallops *a*, the recesses *b* and the design *c* merge or flow into each other to produce a distinctive effect.

I claim:

The ornamental design for a finger ring or similar article, substantially as shown and described.

JOSEPH L. HERZOG.
